(57) CLAIM

The ornamental design for a clothes hanger, as shown and described.

DESCRIPTION

FIG. 1 is a perspective view of a clothes hanger;
FIG. 2 is a front view of the clothes hanger shown in FIG. 1, with a rear view being a mirror image thereof and thus not shown;
FIG. 3 is a left-side view of the clothes hanger shown in FIG. 1;

FIG. 4 is a right side view of the clothes hanger shown in FIG. 1;

FIG. 5 is a top view of the clothes hanger shown in FIG. 1; and,

FIG. 6 is a bottom view of the clothes hanger shown in FIG. 1.

The designations of the views below as top, bottom, right side, left side, front, and rear are for ease of discussion only and are not intended to limit the clothes hanger to one particular orientation. The clothes hanger can be oriented in other directions which would alter these designations. The views are not necessarily shown in the same scale, and any change in scale between different views is not intended to limit the clothes hanger to a particular size.
